UNITED STATES PATENT OFFICE.

PRESTON ELWOOD GILLING, OF SUMTER, SOUTH CAROLINA, ASSIGNOR TO SPLITDORF ELECTRICAL COMPANY, OF NEWARK, NEW JERSEY, A CORPORATION OF NEW JERSEY.

MAGNETO-LAMP.

1,249,063.

Specification of Letters Patent.

Patented Dec. 4, 1917.

Application filed January 11, 1917. Serial No. 141,838.

To all whom it may concern:

Be it known that I, PRESTON E. GILLING, a citizen of the United States, residing at Sumter, in the county of Sumter and State of South Carolina, have invented certain new and useful Improvements in Magneto-Lamps, of which the following is a specification, reference being had to the accompanying drawing.

10 The invention relates to new and useful improvements in combined generating and lighting devices and more particularly to devices of this character which are used for bicycles or the like.

15 Prior to my invention generating and lighting devices have been constructed wherein a lamp is associated with the generator and the generator is driven by a driving wheel making contact with the wheel of the 20 bicycle or other vehicle to which the device is attached.

The lamp extends into a reflector which throws the light forward.

An object of the invention is to provide 25 a means for supporting the reflector for the lamp in a generating and lighting device of the above character, which means permits the reflector to be shifted relative to the generating device so that the rays of light may 30 be thrown in a direction parallel to the plane of the wheel.

A further object of the invention is to provide means for attaching the reflector to the supporting casing for the generator 35 which permits the reflector to be readily detached when desired.

In the drawings, which show by way of illustration, one embodiment of the invention;

40 Figure 1 is a side view showing the generator having a reflector attached thereto by my improved means, a portion of the reflector and a portion of the generator being broken away to show the interior structure;

45 Fig. 2 is a plan view, showing the generating and lighting device associated with the wheel of a bicycle and in dotted lines the manner of adjusting the reflector so that the front face of the reflector lies in a 50 plane at right angles to the plane of the wheel; and

Fig. 3 is a sectional view on the line 3--3 of Fig. 1.

My invention is applied to a combined 55 generating and lighting device which in-

cludes a supporting casing in which is mounted an armature and a field magnet which is associated with the armature. The armature extends through the casing and the lamp is attached to the armature shaft 60 so as to rotate therewith and is electrically connected with the generating coil of the armature shaft. A reflector is mounted on the supporting casing and the armature shaft extends through the wall of the reflector so that the lamp is disposed within 65 the reflector. The upper end plate of the casing is provided with a bearing and the reflector is formed with a supporting sleeve which slips over this bearing. Said sleeve 70 has a projecting flange and this projecting flange serves as a means for securing the sleeve and the reflector to the supporting casing. The flange is also extended and slotted to receive a clamping screw and upon 75 releasing the clamping screw the reflector may be angularly adjusted about the supporting bearing and thus the plane of the front face of the reflector shifted relative to the plane of the wheel. 80

Referring more in detail to the drawings, I have shown my invention applied to a combined generating and lighting device consisting of a supporting casing 1, which is provided with end plates 2--2. Located 85 within the supporting casing is a field magnet and a rotating armature which is indicated at 3. This armature is carried by a shaft having a driving wheel 4 at the lower end thereof and the armature shaft carries 90 a sleeve 5 which projects up through an opening 6 in the reflector 7. The sleeve has a threaded socket at its upper end into which a lamp 8 is secured. The connection between the lamp and the armature may 95 consist of an insulated conductor through the armature shaft, or any other suitable arrangement.

The reflector is mounted on a short sleeve 9 which projects downwardly therefrom and 100 carries a flange 10 at its lower end. The upper end plate carries a bearing 11 for the armature shaft and the sleeve 9 fits about this bearing. Mounted on the end plate 2 is an overhanging bracket 12 and this bracket 105 has a forwardly projecting finger 13. The flange 10 is formed with a notch 14, shaped similarly to the finger 13 but slightly larger than the same. Said flange 10 also has a projecting portion 15 which is formed with 110

a slot 16 lying in the arc of a circle the center of which is the center of the sleeve 9. A rod extends through the casing and joins the two end plates 2—2 and this rod carries 5 a nut 17. The rod extends through the slot 16 and when the nut is screwed down it firmly clamps the flange of the reflector against the upper end plate 2.

From the above it will be apparent that 10 when the nut 17 is loosened the reflector may be shifted about the bearing 1 as a center, that is, about the axis of the armature shaft within the limits of the slot 16.

In Fig. 2 of the drawings, I have shown 15 the generating and lighting device as applied to a bicycle having a wheel 18. The driving wheel 4 of the generator bears against this wheel 18 and thus the armature is driven. It is essential that the front face of the 20 reflector shall lie in a plane which cuts the plane of the wheel at right angles so that the rays of light will be thrown forward in a direction parallel with the plane of the wheel. After the generating and lighting 25 device has been secured to the wheel the reflector may be adjusted as indicated in full lines in Fig. 2, to bring the front face of the reflector into the line A—B, which lies in a plane at right angles to the plane of the 30 wheel 18. It is readily secured in this adjusted position by tightening the nut 17.

When it is desired to remove the reflector for any purpose the nut 17 is taken off, the rod withdrawn from the slot, and then the 35 reflector turned until the notch 14 is in register with the pin 13 which permits the reflector to be lifted from the bearing 11.

It is obvious that minor changes in the 40 details of construction and arrangement of parts may be made without departing from the spirit of the invention, as set forth in the appended claims.

Having thus described my invention, what 45 I claim as new and desire to secure by Letters Patent, is:—

1. A generating and lighting device for bicycles or the like including a supporting casing, a reflector carried by said supporting casing, a lamp located in said reflector and 50 supported independently thereof, and means

for adjusting the position of the reflector relative to the supporting casing whereby the front face of the reflector may be placed in a plane at right angles to the plane of the wheel of the bicycle regardless of the position of the supporting casing. 55

2. A generating and lighting device for bicycles or the like including a supporting casing, an armature within said casing, bearings carried within the casing for the armature shaft, a reflector carried by the supporting casing into which the armature shaft extends, a lamp carried by said armature shaft and means whereby said reflector may be adjusted about the axis of said armature 60 shaft. 65

3. A generating and lighting device for bicycles and the like including in combination a supporting casing having bearings, an armature shaft located in said bearings and projecting therefrom, a reflector having an opening through which said armature shaft projects, a lamp carried by the armature shaft, a sleeve supporting said reflector, said sleeve engaging the bearing for the armature 70 shaft adjacent the reflector, a flange formed integral with said sleeve, said flange having a slotted extension and locking means extending through the slot in said extension for securing the reflector in adjusted positions. 75

4. A generating and lighting device for bicycles or the like including in combination a supporting casing having bearings for an armature shaft, an armature shaft located in said bearings and projecting therefrom, 80 a reflector having an opening through which the armature shaft extends, a lamp carried by the armature shaft, a sleeve supporting said reflector, said sleeve being adapted to engage the bearing for the armature shaft adjacent the reflector, a flange formed integral with the sleeve, a bracket carried by the casing, said bracket having a finger overlapping the flange and said flange having a notch adapted to be brought into register 85 with the finger so that the reflector can be removed from the supporting casing. 90

In testimony whereof I hereunto affix my signature.

PRESTON ELWOOD GILLING.
